FORE AND AFT RIGGED VESSEL

Filed July 18, 1931

UNITED STATES PATENT OFFICE

EDWARD L. BLACKMAN, OF BROOKLYN, NEW YORK

FORE AND AFT RIGGED VESSEL

Application filed July 18, 1931. Serial No. 551,603.

This invention relates to fore and aft rigged vessels in general and more especially to the mechanism for rigging sail boats, such as sloops, schooners, catboats or other fore and aft rigged vessels.

The subject matter of this application in part is disclosed in my copending application, Serial No. 480,888 filed September 10, 1930.

Among the objects of the present invention, it is aimed to provide an improved apparatus for rigging the sails of sail boats, such as sloops, schooners, catboats or other fore and aft rigged vessels by means of which when sailing with the wind, the front end of the sails will form an acute angle with the deck of the vessel and when sailing with the wind from any other quarter will extend to leeward so that the sails, when the boat heels with the wind, will lie in a plane more nearly perpendicular to the thrust or direction of the wind so that greater advantage will be taken of the propelling force of the wind.

It is still another object of the present invention to provide in an improved rigging of this type, a reinforcement or stiffening means for the luff edge of the main sail having the required strength and rigidity but having a minimum weight and mass so that the additional weight or mass required may be reduced to a minimum.

It is still another object of the present invention to provide an improved stiffening means for the luff edge of the main sail of a rigging of this improved type which while having the required rigidity and stiffness is sufficiently flexible and mobile to cooperate with the force distributing means resulting in a more even distribution of the force of the wind along the length of the mast.

These and other features, capabilities and advantages of the present invention will appear from the subjoined detail description of one specific embodiment thereof illustrated in the accompanying drawings in which

Figure 1 is a perspective of a fore and aft rigged vessel, of the sloop variety equipped with the present improvement;

Fig. 2 is a plan view of the same showing

the position of the main sail in dotted lines when sailing with the wind;

Fig. 3 is a fragmental view along the line 3—3 of Fig. 2;

Fig. 4 is a fragmental sectional view showing the connection of the boom and flexible connector with the guiding means of the same;

Fig. 5 is an enlarged fragmental view of the upper end of the main sail and its connection to the boom and flexible connector;

Fig. 6 is a fragmental enlarged view similar to Fig. 5 showing another position of the gaff relative to the mast; and

Fig. 7 is a section on the line 7—7 of Fig. 6.

In the embodiment illustrated, there is provided a hull 1 having a mast 2, a jib-boom 3, a main sheet block traveler 4 and a tiller or helm 5, all arranged as customary with vessels of this type.

In the present instance, the jib-boom 3 is provided with an arcuate cross-bar 6 to which is slidably connected the slidale member 7 connected by the block and tackle 8 to the halyard 9, the free end of which is connected to the cleat 10 formed on the deck 1^a of the vessel adjacent to the bow thereof.

The slidale member 7 is connected to the front end of the jib 11, the rear lower end of which is connected by the halyard 12 to the cleat 13 secured on the deck 1^a of the hull to the front of the mast 2. The upper end of the jib 11 is connected to the halyard 14 which extends through the block or pulley 15 secured to the upper end of the mast 2, which halyard 14 then passes down to the cleat 16 secured to the 1^a of the vessel.

The main sail 17 is connected at its lower edge in the usual way to the boom 18 and along its upper edge to the gaff 19. The luff edge of the sail in the present instance is slidably connected to the flexible connector 20 which in the present instance preferably consists of a steel cable of sufficient strength and under sufficient tension to maintain the luff edge substantially straight and sufficiently flexible and mobile to facilitate cooperating with the force distributing means hereinafter to be described.

This connector 20, see particularly Fig. 5

is preferably connected at its upper end to a metallic thimble 21 which encircles the mast 2 flaring inwardly at its upper edge at 22 to form a smooth cam surface with the 5 mast 2 and inwardly rounded at its lower edge at 23 to form a cam surface. This thimble 21 has an enlargement 24 at one edge thereof, preferably to the rear of the mast 2 to form an anchoring chamber for the upper 10 end of the connector 20 in which it is properly secured in any suitable manner. The lower end of the connector 20, see Fig. 4 is provided with a coupling member 25 pivotally connected at 26 to the projection 27 15 which is fixed to the upper end of the gripping bracket 29 and passes through an opening 28' in the metal bracket 28 to permit the metal bracket 28 to be pivotally mounted on said projection 27. The connection of the 20 projection 27 with the metal bracket 28 permits not only rotation of the boom 18 about a substantially vertical axis but in addition permits rocking about a horizontal axis.

The projection 27 as shown in Fig. 4 is 25 fixed to the upper end of the gripping bracket 29, the jaws of which grip the upper flange 30 of the I-beam rail 31. The front end of the gripping member 29 is provided with a projection 31 provided with an opening 32 to receive the halyard 33 of the block and tackle 34. The free end of the halyard 33, as shown in Fig. 1, is connected to the cleat or hook 35 formed on the deck 1^a of the vessel adjacent to the tiller 5.

35 The lower pulley 36 of the block and tackle 34 is connected to the deck 1^a of the vessel at 37, preferably to the rear of the mast 2 as indicated.

The rail 30 in the present instance, preferably extends from starboard side to larboard side of the vessel as indicated being mounted on the standards 38 and 39, and is arcuate, the radius of which coincides with the distance from the upper end of the connector 20 to the lower end thereof to permit the lower end of the connector 20 to travel along this rail 30 while maintained in a perfectly rigid position.

At both ends of the rail 30, there are provided the extensions 40 and 41 respectively, the front ends of which are mounted on the standards 42 and 43, and these extensions 40 and 41 are similarly arcuate, the radii of which coincide with the distance from the upper end of the connector 20 to the lower end thereof to permit the lower end of the connector 20 to travel in such extensions 40 and 41 while being maintained substantially rigid. The front ends of the rail extensions 60 are provided with the abutments 44 to determine the forward movement of the connector 20 relative to the extensions 40 and 41 respectively.

Throughout the length of the connector 20, 65 there are provided a plurality of rings or

loops in the present instance five being shown, to wit the rings 45, 46, 47, 48 and 49, the same graduating in length, the uppermost one 45 being the smallest and the lowermost one 49 being the longest, the respective sizes of these 70 rings 45 to 49 inclusive, as will appear from Fig. 1 to correspond to the varying distance of the connector 20 from the mast 2 when the lower end of the connector 20 engages the extensions 40 and 41 or the ends of the rail 30. 75

When it is desired to reef the main sail 17, it is only necessary to swing the boom 18 so that its forward end is disposed adjacent to the rear of the mast 2 when the distance is such that the smallest ring 45 may pass over 80 the connector 20 and mast 2 at their lower extremities adjacent to the rail 30.

The gaff 19 is provided at its inner end with the wooden bifurcated member 50 which is preferably provided with a flexible pin 51 on which are preferably mounted the wooden rings 52 which act as ball bearings when engaging the mast 2 as shown in Fig. 7. The trough of the bifurcated portion 50 is preferably provided with a metallic sheet 53 to 90 take up the wear to which this end of the device 50 is subjected when passing up and down along the connector 20.

The gaff 19 is provided with the usual halyards, to wit the peak halyard 54 extending from the upper end of the gaff 19 to the pulley 55 secured to the upper end of the mast 2 and then passing down to the pulley 56 midway between the ends of the gaff 19 and then back to the pulley 55 and then down 100 to the deck of the vessel in the usual way. The inner end of the gaff 19 is also provided with the usual throat halyard 57 which passes around the pulley 58 connected to the inner end of the gaff 19 and then up around the 105 pulley 59 at the upper end of the mast and then down to the deck in the usual way.

The free end of the boom 18 is provided with the usual main sheet block and tackle 60 which is connected to the traveler 4, the 110 halyard of which extends forwardly to the cleat 61 adjacent to the pivotal mounting of the tiller 5.

It will be seen from Figs. 5 and 6 that the device 50 is constructed freely to pass over the thimble 21 from the position indicated in Fig. 5 to the position indicated in Fig. 6 when the gaff is lowered in the act of reefing the sail, and on the other hand that this device will freely pass over the thimble 21 when moving upwardly in the act of unreefing or raising the sail, when the cam surface 23 will facilitate the smooth upward movement of the device 50.

In order to brace or reinforce the mast, in 125 the present instance, the stays 62 and 63 are provided consisting of steel cables connected to the upper end of the mast 2 and provided with hooks 64 and 65 respectively at their lower ends which engage the block and tackle 130

66 and 67 respectively secured to the deck 1^a just astern of the guide rail 30, and the free ends of the halyards 68 and 69 of such block and tackle 66 and 67 respectively are connected to the cleats 70 and 71 formed on the deck 1^a.

It is obvious that various changes and modifications may be made to the details of construction, as for instance when applied to 10 a Marconi rig, leg-of-mutton rig or the like, without departing from the general spirit of the invention as set forth in the appended claims.

I claim:

15 1. A fore and aft rigged vessel having a mast and flexible connector connected at its upper end to the upper portion of the mast to be spaced to the leeward or windward from the lower portion of the mast and to be held 20 taut in such positions, a gaff positioned substantially at the upper end of the taut connector, a boom connected to said connector substantially at its lower end, and a sail connected to the gaff, connector and boom.

25 2. A fore and aft rigged vessel having a mast and rail extending from one side of the vessel to the other adjacent to said mast, a cable connected at its upper end to said mast and at its lower end to said rail and held 30 taut but movable so that it may be inclined to leeward or windward of said mast, a gaff secured to the mast substantially at the upper end of said cable, a movable connection, a boom connected near the lower end of said 35 cable to said rail by said movable connection, a main sail connected to said gaff, cable and boom, a jib boom connected to the bow of said vessel, a crossbar secured to said jib boom, and a jib sail connected at its upper 40 end to said mast and at its front end to said crossbar, there to be inclined to leeward or windward of said vessel and at its rear end attached to said vessel.

3. A fore and aft rigged vessel having a 45 mast, a flexible connector connected to the upper portion of the mast and extending down to and adapted to be spaced from the lower end of the mast, and a main sail connected at its luff edge to said connector.

50 4. A fore and aft rigged vessel having a mast, a flexible connector connected at its upper end to the upper portion of the mast and extending down to and spaced from the lower end of the mast, a main sail connected 55 to said connector, and a plurality of connecting means along said connector and mast to distribute the strain of the sail throughout the length of the mast.

5. A fore and aft rigged vessel having a 60 mast, a boom, a sail attached along its lower edge to the boom and attached at the upper end of the luff edge of the sail to the mast; a flexible connector, means for holding the luff edge of the sail substantially straight, a 65 fixed and rigid guide secured to and extend-

ing across the deck of the vessel abaft the mast, to which said guide, said boom is attached to be shifted from side to side of the vessel.

6. A fore and aft rigged vessel having a 70 mast, a cable connected at its upper end to the mast and at its lower end adapted to be spaced to leeward or windward from the lower portion of the mast, a boom connected at the lower end of the cable, a sail connected to the cable and boom, and means for connecting the lower end of the cable to the vessel and being spaced from the lower end of the mast to maintain the sail more nearly 75 perpendicular to the horizontal plane of the wind whereby the propelling effect of the wind pressure on the sail is increased.

7. A fore and aft rigged vessel having a mast, a connector, a coupling for connecting the upper end of the connector to the mast, a boom connected to the lower end of the connector, a gaff, and a sail connected to the gaff, connector and boom, said gaff having a jaw at its inner end for receiving the mast and connector to permit the gaff to pass the 90 mast and connector when lowered in the act of reefing or furling the sails.

8. A fore and aft rigged vessel having a mast, a flexible connector, a thimble secured at the upper end of the connector to said mast, a boom, a gaff, a sail connected to said boom, connector and gaff, and means at the inner end of said gaff for slidably mounting said gaff on said mast and connector.

9. A fore and aft rigged vessel having a 100 mast, a boom, a flexible connector connected at its upper end to the upper portion of the mast, a rail extending abaft the mast across the deck of the vessel, a gripping jaw on said rail, a projection extending upwardly from 105 said gripping jaw and pivotally connected to the lower end of said connector, a bracket on the inner end of said boom pivotally connected to said projection, a gaff slidably mounted on said mast and connector, and a 110 sail connected to said boom, connector and gaff.

10. A fore and aft rigged vessel having a mast, a rail extending abaft the mast and across the deck of the vessel, a flexible connector connected at its upper end to said mast and at its lower end slidably connected to said rail, said boom being pivotally connected to the lower end of said connector, a gaff 115 slidably mounted on said mast and connector, and a sail connected to said mast, connector and gaff.

11. In a fore and aft rigged vessel having a mast, a rail extending abaft the mast across the deck of the vessel and spaced a short distance from said mast directly abaft said mast, a flexible connector connected at its upper end to the upper portion of said mast and slidably mounted on said rail at its lower end, a boom connected to the lower end of 120 125 130

- said connector, a gaff slidably mounted on said mast and connector, a sail connected to said connector, boom and mast, and graduated rings connected to said sail, the smallest 5 at the top and the largest at the bottom, gradually enlarging as they approach the lowermost ring, said rings extending from said sail around said mast and connector, the smallest ring at the top being large enough 10 to pass both the connector and the mast when the connector is disposed directly abaft the mast in order to permit reefing the sails.
12. In a fore and aft rigged vessel having a mast, a rail extending abaft the mast across 15 the deck of the vessel and spaced a short distance from said mast directly abaft said mast, a flexible connector connected at its upper end to the upper portion of said mast and slidably mounted on said rail at its lower end, a boom connected to the lower end of said connector, a gaff slidably mounted on said mast and connector, a sail connected to said connector, boom and mast, and graduated loops connected to said sail, the smallest at the top 20 and the largest at the bottom, gradually enlarging as they approach the lowermost loop, said loops extending from said sail around said mast and connector, the smallest loop at the top being large enough to pass both the 25 connector and the mast when the connector is disposed directly abaft the mast in order to permit reefing the sails, said loops substantially equal to the distance from the mast to the connector when the sail is in raised position and the connector is in its extended lateral position whereby such loops will distribute the force of the wind throughout the 30 length of the mast.
13. A fore and aft rigged vessel having a mast, a flexible connector, a coupling connected at the upper end of said connector to the upper portion of said mast and having cam surfaces at its ends, a boom connected to the lower end of said connector, a gaff, a gripping jaw on the inner end of said gaff to receive said mast and connector, a metallic reinforcement at the inner end of said gripping jaw adjacent to the connector when the gaff is moved down along said connector, and a sail connected to said boom, connector and gaff.
14. A fore and aft rigged vessel having a mast, a rail extending from one side of the vessel to the other adjacent to said mast, a cable connected at its upper end to said mast and its lower end to said rail to incline to leeward or windward of said mast, a boom connected to the lower end of said cable, a main sail connected to said cable and boom, a jib-boom connected to the bow of said vessel, a crossbar secured to said jib-boom, and a jib-sail connected at its upper end to said mast and at its front end to said crossbar there to be inclined to leeward or windward of said vessel and at its rear end attached to said vessel.
15. A fore and aft rigged vessel having a mast, a cable connected to the upper portion of said mast with its lower end movable 70 across the deck of the vessel, means for anchoring the lower end of the cable in any desired position across the deck of the vessel either parallel to the mast or at an angle thereto, and a main sail slidably attached to the cable to be hoisted or lowered along said cable.
16. A fore and aft rigged vessel having a mast, a cable connected to the upper portion of said mast with its lower end movable across 80 the deck of the vessel, means extending partly around the mast for anchoring the lower end of the cable either parallel to the mast or at an angle thereto, as desired, and a main sail slidably attached to the cable to be hoisted or lowered along said cable.
17. A fore and aft rigged vessel having a mast, a flexible connector connected at its upper end to the upper portion of the mast and at its lower end adapted to be spaced from the lower end of the mast, a fixed guide secured to and extending across the vessel but spaced from the lower end of the mast, the lower end of the connector being movable on said guide, and a main sail connected to said connector.
18. A fore and aft rigged vessel having a mast, a cable connected at its upper end to the mast and at its lower end adapted to be spaced to leeward or windward from the lower portion of the mast, a gaff positioned at the upper end of the cable, a boom connected at the lower end of the cable, a sail connected to the gaff, cable boom, and means connecting the lower end of the cable to the vessel spaced from the lower end of the mast to maintain the sail more nearly perpendicular to the horizontal plane of the wind whereby the propelling effect of the wind pressure on the sail is increased.
19. A fore and aft rigged vessel having a mast, a rail extending from one side of the vessel to the other adjacent to said mast, a cable connected at its upper end to said mast and its lower end to said rail to incline to leeward or windward of said mast, a gaff, a boom connected to the lower end of said cable, a main sail connected to said gaff, cable and boom, a jib-boom connected to the bow of said vessel, a crossbar secured to said jib-boom, and a jib-sail connected at its upper end to said mast and at its front end to said crossbar there to be inclined to leeward or windward of said vessel and at its rear end attached to said vessel.
20. A fore and aft rigged vessel having a mast, a flexible connector connected at its upper end to said mast, a boom connected to the lower end of said connector, and a sail con- 130

nected to said connector and boom and adapted to be moved to form an acute angle with the deck of the vessel and into position more nearly perpendicular to the horizontal plane of the wind resulting in increased efficiency of the propelling effect of the wind.
